UNITED STATES PATENT OFFICE.

RAYMOND A. RODRICK, OF AKRON, OHIO, ASSIGNOR TO CLARENCE W. WHITE, OF AKRON, OHIO, AND HIMSELF.

WINDSHIELD CLEANER.

Application filed March 8, 1926. Serial No. 93,065.

This invention relates to new and novel improvements in power operated devices for actuating a reciprocating element and while it is adapted for use generally, it is particularly designed to be employed in connection with a wind shield cleaner.

The invention relates to the same general type of device as is shown and described in my pending application, Serial Number 10 741,087, filed October 1, 1924, and aims to provide certain improvements and modifications in the structure therein shown.

Objects of the invention are to provide a power operated wind shield cleaner or like device which may be manufactured at a low cost and which in use will be extremely efficient and reliable.

A particular object is to provide a new and improved casing adapted to be secured across 20 the top of the wind shield and to provide new and improved driving elements therein whereby a carriage carrying a wind shield cleaner may be carried longitudinally of the casing without vibration and without noise.

A further object is to provide a device of the character above indicated having a new and novel arrangement of spiral springs, one arranged to drive a reciprocating element in one direction in a casing and the other arranged to drive the reciprocating element in the other direction and to provide new and improved means for shifting the reciprocating element from one of the springs to the other.

The above objects are accomplished and additional ends are attained by the novel construction, combination and arrangement of parts hereinafter described and illustrated in the accompanying drawing, wherein I have shown a preferred form of the invention, it being understood that the invention is capable of various adaptations and that changes and modifications may be made or resort had to substitutions which come within the spirit 40 of the invention as set forth in the appended claims.

In the drawings like numerals of reference are employed to denote like parts as the same may appear in any of the several views and in which:—

Figure 1 is a side elevational view of a wind shield cleaner constructed in accordance with this invention showing the same

partly in cross section to more clearly illustrate the relation of its several elements.

55

Figure 2 is a top view showing the same with the casing removed.

Figure 3 is a sectional view taken as indicated by the lines 3—3 of Figure 1.

Figure 4 is a perspective view showing one 60 of the end plates employed in reducing the invention to practice.

Figure 5 is a perspective view of a portion 65 of the casing constructed in accordance with this invention.

65

Figure 6 is a plan view of one face of the motor casing.

Proceeding now to a detailed description of the invention with reference to the particular adaptation thereof shown in the drawings, 70 the reference character A is used generally to denote an elongated casing adapted to be secured to the outer face of the wind shield so as to extend transversely across the top thereof. The rear face of the casing or the 75 side presented to the windshield is provided with a longitudinally extending slot 10. The casing is provided on the interior face of the forward and rear walls thereof with longitudinally directed, oppositely disposed channels 11 and 12. The casing is also provided on the interior face of the bottom wall thereof with two longitudinally directed, parti-cylindrical channels 13 and 14. While the casing may be formed in any suitable manner, 80 I prefer to form the main body thereof of one piece of sheet metal which is drawn or stamped to form a longitudinal box-like structure. The upper portion of the rear wall 15 extends upwardly from the slot 10. 90

The upper wall is denoted by the reference character 16 and the forward wall by the reference character 17. The forward wall is pressed inwardly as at 18 to form the in-wardly projecting longitudinally extending 95 rib 19, one face of which forms the upper wall of the channel 12. The lower portion of the forward wall 17 is stamped inwardly as at 20 to form the longitudinally directed tubular portion 21 which surrounds the seat 100 13. The lower wall is likewise formed to provide a parti-cylindrical portion 22, the lower wall being provided centrally thereof with the upwardly stamped portion 23 which forms a dividing wall between the tubular seats 13 and 14. The rear wall is provided

105

in spaced relation to the lower edge thereof with an inwardly stamped portion 24 which forms a portion of the cylindrical wall of the seat 14 and the lower wall of the channel 11.

The material is turned inwardly at the lower edge of the slot 10 to provide the inwardly projecting lip 25 which forms the upper wall of the channel 11. The longitudinally directed seats 13 and 14 are cylindrical in form, each being open along the upper side thereof for a purpose hereinafter described.

The reference character B is used to denote an electric motor which may be of any desired construction. The forward face 26 of the motor casing is provided with a cavity 27; the rotor 28 of the motor is mounted on a shaft 29. The shaft 29 is provided on the forward end thereof with a threaded axial bore 30 in which is threaded a shaft 31. The shaft 31 extends through a suitable bore in the forward wall 26 and a spur gear 32 is positioned in the cavity 27 and operatively fixed on said shaft.

The numeral 33 denotes a similar spur wheel which is in mesh with the wheel 32 and which is mounted in said cavity 27 on the shaft 31. The numeral 35 denotes a plate which forms one end of the casing A and which is secured against the face 26 by means of the screws 36, thus enclosing the cavity 27. The numeral 37 denotes a block which is shaped to fit the interior of the casing A and which is secured flat against the plate 35 by means of the screws 38 or other suitable fastening means. The end plate 35 is secured to the casing A by inserting the block 37 into one end of the casing with the end of the casing in contact with the end plate 35. Suitable pins or screws 39 are positioned through suitable bores in the casing and secured in suitable bores 40 in said block thereby securing the end plate 35 firmly in place. The block 37 and the plate 35 are provided with parallel bores 41 and 42 which are adapted to receive the shafts 31 and 34 which project therethrough into the casing 10. The inwardly projecting portion of the shaft 31 is provided with a right hand screw thread and the inwardly projecting portion of the shaft 34 is provided with a left hand screw thread. A threaded collar 43 is threaded on the inwardly projecting end of the shaft 31 and a similar collar 44 is threaded on the forwardly projecting end of the shaft 34.

The numeral 45 denotes a stub shaft which is provided on one end thereof with a right hand thread which is threaded in the collar 43. The other end of the stub shaft 45 terminates in a point 45^a. The numeral 46 denotes a similar stub shaft which is provided on one end thereof with a left hand screw thread and is operatively secured in the collar 44, the other end of the stub shaft 46 like-

wise terminating in a point 46^a. The numeral 47 denotes a spiral spring which is secured to the stub shaft 45 at a point in spaced relation to the collar 43. The spring 47 is positioned in the seat 13 and extends therethrough to a point in spaced relation to the other end of the casing.

The numeral 48 denotes a like spiral spring which is secured to the stub shaft 46 at a point immediately forward from the collar 44. The spiral spring 48 extends longitudinally through the seat 14 and terminates at a point in spaced relation to the other end of the casing. It will be noted that the secured end of the spring 48 is positioned closer to the wall 35 than the secured end of the spring 47 and that the free end of the spring 47 projects beyond the free end of the spring 48. The springs 47 and 48 form screw driving elements having a diameter slightly smaller than the seats 13 and 14 and the walls of said seats extend around said screws leaving a gap substantially narrower than the diameter of the springs, thereby securely holding the springs 47 and 48 in their proper position. The other end of the casing is provided with an end wall 49 to which is suitably secured a block 50 which is similar to the block 37. The block 50 is secured to the end wall 49 and is inserted into the end of the casing to which it is secured by means of the screws 51 which are introduced through the walls of the casing into suitable bores in the side wall of said block 50.

The numeral 52 denotes packing rings which extend around the lower, forward and rear walls of both ends of the casing to enclose the packing 53, thus rendering fluid tight each end wall of each casing. The shaft 31 is secured in the end of the rotor shaft 105 with a right hand thread, but it is to be understood that a motor may be used which operates in a reversed direction in which case a reverse threading system would be used.

The numeral 54 denotes a carriage which is provided on the forward and rear sides thereof with a plurality of rollers 55, these rollers are entered in the channels 11 and 12 so as to normally operate on the lower walls thereof and are arranged to contact with the lower or upper walls of said channels. The carriage is provided at a point above the rollers 55 with a plurality of rollers 56 which are mounted on a vertical axis so as to contact with the inwardly projecting flange 25 and the inwardly pressed rib 19. It will thus be seen that the carriage is provided with a double set of rollers whereby it will be held in longitudinal alignment in said casing and may be freely moved longitudinally thereof with a minimum of friction.

The numeral 57 denotes a finger which depends from the carriage 54 and is pivotally secured thereto by means of the pin 58, whereby the said finger 57 may be swung into op-

erative engagement with either of the springs 47 or 48. The finger 57 projects upwardly from the pin 58 to form the upwardly projecting portion 57^a. The upwardly projecting portion 57^a of the finger 57 is loosely secured in the loop lever 59 which is pivotally mounted for horizontal swinging movement on the pin 60 which is suitably secured in the carriage 54 at a point in spaced relation to the finger 57. An oppositely projecting loop 61 is also pivotally secured on the pin 60 and a spring 62 has one end secured to the free end of the loop 61 and the other end secured to the free end of the loop 59 whereby a movement of the loop 61 in either direction past the center will cause the spring 62 to move the loop 59 in the same direction.

The numeral 63 denotes a finger which projects upwardly from the free end of the loop 61. The numeral 64 denotes flat springs one of which is secured to each side of the casing by means of a pin 65 or other suitable means. The spring 64 extends across the casing at an angle, with the spring at one end of the casing secured to an opposite wall thereof and being oppositely disposed relative to the first named spring 64.

A movement of the carriage 54 toward the end of the casing will cause the finger 63 to be engaged by the inclined face of one of the springs 64 whereby a further movement of the carriage 54 will shift the finger 57 from one of the springs 47 or 48 to the other, thereby moving the carriage in the opposite direction.

The numeral 65 is used to denote an arm which is secured to the carriage 54 and projects outwardly through the slot 10. As shown in Figure 3, the arm projects downwardly and forwardly and terminates at a point beneath the casing A. The arm 65 is provided with a suitable eye 66 to which a wind-shield cleaning member (not shown) may be attached.

When used as a wind shield cleaner on an automobile, the device is attached to the outside of the wind shield or the automobile top so as to extend across the upper part of the wind shield. A wiping element is secured to the arm 65 and the electric motor B is operatively connected to the battery or electric generator with which the automobile is equipped.

To use the device, the motor B is operated, thus rotating each of the springs 47 and 48. It will be seen that the carriage 54 will be driven by the spring 48 until it has reached the free end of said spring. At this point the finger 63 is engaged by the spring 64 and the arm 61 is operated to throw the finger 57 into operative engagement with the spring 47. Inasmuch as the spring 47 projects beyond the spring 48, the shifting movement is quickly and easily accomplished. The spring 48, which is operating in the opposite direc-

tion, engages the finger 57 and drives the carriage in the opposite direction. As it reaches the other end of the casing, the finger 57 leaves the end of the spring 47 simultaneously with the shifting movement caused by the finger 63 being engaged by the inclined spring 64. This shifting movement causes the finger 57 to be again engaged by the spring 48, thus driving the carriage in the opposite direction.

Having thus illustrated my invention and described the same in detail, what I claim as new and desire to secure by Letters Patent is:—

1. In a device of the class described, a casing having a bottom formed to provide two parallel parti-cylindrical, longitudinal extending seats, a spiral spring rotatably mounted in each seat, means to rotate said springs in opposite directions; inwardly directed, longitudinally extending ribs projecting into said casing, said ribs forming grooves in both the forward and rear walls of said casing, a carriage mounted for movement longitudinally of said casing, said carriage having rollers mounted in said grooves and rollers operating on certain of said ribs to maintain the carriage in longitudinal alinement with said casing; a shiftable finger on said carriage, means normally holding said finger in operative engagement with either of said springs and means for shifting the finger from one spring to the other, said means automatically operable as the carriage is moved to either end of the casing.

2. In a device of the class described, a casing having a longitudinally extending slot along one side thereof, the bottom of said casing formed to provide two parallel parti-cylindrical, longitudinally extending seats, a spiral spring rotatably mounted in each seat, means to rotate said springs in opposite directions; inwardly directed, longitudinally extending ribs projecting into said casing from both the forward and rear walls thereof, a carriage mounted for movement longitudinally of said casing, said carriage having rollers mounted between said ribs to maintain said carriage in longitudinal alignment with said casing, a shiftable finger on said carriage, means normally holding said finger in operative engagement with either of said springs and means for shifting the finger from one spring to the other, said means automatically operable as the carriage is moved to either end of the casing, an arm on said carriage, said arm projecting from said slot.

3. In a device of the class described, a casing having top, side and bottom walls formed of one piece of sheet material, the bottom wall formed to provide two parallel parti-cylindrical, longitudinally extending seats, a spiral spring rotatably mounted in each seat, means to rotate said springs in opposite directions, longitudinally directed guide ribs projecting into said casing from each side wall

- thereof, a carriage mounted on said guide ribs for movement longitudinally of said casing; a shiftable finger on said carriage, means normally holding said finger in operative engagement with either of said springs and means for shifting the finger from one spring to the other, said means automatically operable as the carriage is moved to either end of the casing.
10. 4. In a device of the class described, a casing, a carriage mounted therein for movement longitudinally thereof, a spiral spring for moving the carriage in one direction, a spiral spring for moving the carriage in the opposite direction, means to externally support said spring and hold the same in a straight line over its entire length and means to rotate said springs.
15. 5. In a device of the class described, a casing, a carriage mounted therein for movement longitudinally thereof, a spiral spring for moving the carriage in one direction, a spiral spring for moving the carriage in the opposite direction, said casing forming a seat snugly enclosing each spring around the greater part of its circumference, a finger on said carriage, said finger shiftable into operative engagement with either of said springs and means operable to shift said finger from one spring to the other.
20. 6. In a device of the class described, a casing, a carriage mounted for movement longitudinally thereof, a rotatably mounted spiral
- spring for driving the carriage in one direction, a like spring for driving the carriage in the opposite direction and means extending longitudinally of said spring to engage the same around the greater part of its circumference to maintain each spring in a certain position in said casing.
25. 7. In a device of the class described, a carriage, a spiral spring for driving the carriage in one direction, a spiral spring for driving the carriage in the opposite direction and external means to support and hold each of said springs in an operative position.
30. 8. In a device of the class described, a casing, two parallel, parti-cylindrical seats formed in the wall of said casing, a screw driving member rotatably mounted in each seat, each of said seats enclosing the greater part of the circumference of the driving member mounted therein and extending longitudinally thereof.
35. 9. In a device of the class described, a casing provided on the interior face thereof with a seat corresponding in cross section to the greater part of a circle, a rotatable spiral spring driving member snugly received in said seat, a carriage moveable longitudinally of said casing and a shiftable driving connection between said driving member and said carriage.
40. In testimony whereof I have hereunto set my hand.
45. RAYMOND A. RODRICK.
